M. K. ENA.

BED PAN.

APPLICATION FILED JUNE 6, 1918.

1,297,813.

Patented Mar. 18, 1919.

Inventor,
Maria K. Ena;

By *Raymond K. Webster*,

Her Attorney

UNITED STATES PATENT OFFICE.

MARIA K. ENA, OF LOS ANGELES, CALIFORNIA.

BED-PAN.

1,297,813.

Specification of Letters Patent. Patented Mar. 18, 1919.

Application filed June 6, 1918. Serial No. 238,589.

To all whom it may concern:

Be it known that I, MARIA K. ENA, a citizen of the United States, residing at Los Angeles, in the county of Los Angeles and State of California, have invented new and useful Improvements in Bed-Pans, of which the following is a specification.

This invention relates to bed pans, and it has for its object to provide an improved device or utensil of this character, which will be superior in point of relative simplicity and inexpensiveness in manufacture; convenience in use and in disposition when out of service; facility in cleaning, maximum capacity in conjunction with compactness in form, and which will be generally superior in efficiency and serviceability.

With the above and other objects in view, the invention consists in the novel and useful provision, construction, formation, combination, association and relative arrangement of parts, members and features, all as hereinafter described, shown in the drawing, and finally pointed out in claims.

In the drawing:

Figure 1 is a top plan view of an improved bed pan constructed and organized to embody the invention;

Fig. 2 is a side elevation of the same with a portion of the lid or cover or door thereof in elevated position, such part being shown in depressed position in Fig. 1;

Fig. 3 is a bottom plan view of the same partly broken away for fullness of illustration;

Fig. 4 is a vertical transverse sectional view of the same, taken upon the line x^4-x^4 , Fig. 1; and

Fig. 5 is a fragmentary side elevation, similar to Fig. 2, the entire lid, door or closure being, however, shown in raised position.

Corresponding parts in all the figures are designated by the same reference characters.

Referring with particularity to the drawing, the improved bed pan comprises an elongated vessel or body 5, tapering sharply toward its forward end portion 6, and lies pronouncedly toward its rear end portion 7, at which ends respectively it may be provided with a loop or eye 8 for suspending the bed pan from a hook or nail or the like, and with a handle 9 whereby it may be carried, or whereby also it may be suspended. The body 5 is of increasing depth toward its median portion, and tapers in depth toward

its end portions, and is provided with a top opening normally covered by a lid, cover or closure A. It will be understood that the body 5 includes side, end, top and bottom 60 walls, capable of holding liquid contents, and that the closure A may be manipulated to open up the vessel at the top, for use, and for removing the contents and cleaning the interior. The closure A is hinged to the top 65 of the body 5, at as 10, and comprises a main hinged member *a* and a secondary hinged member *b*; such main member being preferably hinged to the body as at 10, and the secondary member *b* being hinged to the member *a* as at 11. Such hinge lines extend in angularity each to the other, preferably at an angle of 90 degrees, so that the entire lid or cover A may be hinged at its side so as to tilt it upwardly and crosswise of the 75 body 5; and when the member *a*, so hinged at its side as at 10, is closed, the member *b* may be moved upon its hinge upwardly and lengthwise of the body 5. The member *b* may thus be swung upwardly and rearwardly onto the member *a*, to permit access to the interior of the vessel, for use of the same, and the entire closure A upon its main 80 hinges 10 may swing open, for use if desired or necessary, or for purpose of removing the 85 contents of the device or cleansing the interior of the same. A latch device or fastening means *c* is provided at the forward end of the body to coöperate with a pin or stud 12 upon the closure member *b*, for the purpose of holding down the entire closure A, with its two members, tight upon the body 5; and the closure member *a* may, if desired, have a finger-piece 13 whereby it and the member *b* may be jointly manipulated. The 90 members *a* and *b* of the closure A are preferably provided with flanged and lipped edge portions 14, having an overlapping flange fit in connection with flanges 15 upon the edge portions of the opening which such closure is 95 applied to, such flanges 15 extending downwardly into such opening. This insures a tight and a sanitary fit of the closure to the body 5.

In the use of the bed pan the forward 105 end portion 6 with its sharp diminution in depth, toward the central deepest portion of the vessel, will be found capable of convenient introduction into position for service, and the pronounced downward bulge in the 110 central portion of the body produces a capacity of the vessel which is maximum for a

bed pan of the size and dimensions and other features of convenience and comfort involved. The closure members may be readily manipulated either to entirely or 5 partially open the device, and may be held jointly in closed position by the latch device *c*, effectively and in a sanitary manner sealing up the contents of the vessel, largely due to the provision of the coöperating 10 flange formations of the closure and body, at 14 and 15. The device may be conveniently handled, and suspended when out of use, by means of the handle 9 and the loop or eye 8.

15 It is manifest that many and various changes may be made in the construction, formation, association, combination, and provision of parts, members and features, all with respect to the specific showing of 20 the foregoing description and drawing, in adapting the invention to varying conditions of use and service, without departing from the true spirit of the invention.

Having thus disclosed my invention, I 25 claim and desire to secure by Letters Patent:

1. A bed pan including an elongated receptacle having a maximum depth at an intermediate point in its length, the side and 30 end walls being carried inwardly at the top thereof and defining an opening, a cover for closing the opening, said cover being formed in hingedly connected sections one of which is adapted to be swung back upon the other 35 section to partially uncover the opening, and a hinge connection between the said other section of the cover and an edge of the opening.

2. A bed pan including an elongated receptacle having a maximum depth at an intermediate point in its length, the side and 40 end walls being carried inwardly at the top thereof and defining an opening, a cover di-

vided transversely into two sections which are hingedly connected so that one section 45 can be swung rearwardly upon the other section to partially uncover the opening, and a hinge connection between one section of the cover and an edge of the opening, the two hinge connections being arranged at an angle to each other.

3. A bed pan including an elongated receptacle having side and end walls which are carried inwardly at the top thereof and define an opening, an inturned peripheral 55 flange extending around the opening, a cover for closing the opening formed with a peripheral flange which nests tightly within the peripheral flange of the opening, said cover being formed in hingedly connected 60 sections so that one section can be swung upon the other section to partially uncover the opening, and a hinge connection between one section of the cover and an edge 65 of the opening.

4. A bed pan including an elongated receptacle having a maximum depth at an intermediate point in its length and tapering toward both ends thereof, the side and end walls being carried inwardly at the top of 70 the receptacle and defining an opening, a cover closing the opening and divided transversely into two sections which are hingedly connected so that one section can be swung upon the other section to partially uncover 75 the opening, and a hinge connection between the said other section of the cover and an edge of the opening.

In testimony whereof, I have signed my name to this specification in the presence of 80 two subscribing witnesses.

MARIA K. ENA.
